UNITED STATES PATENT OFFICE

2,507,951

SERVER DEVICE

James F. Barnes, Chicago, Ill.

Application July 31, 1948, Serial No. 41,803

2 Claims. (Cl. 211—129)

1

This invention relates to a food server device, and more particularly to a device known as a "Lazy Susan" server. The server is particularly useful in the serving of relishes, hors d'oeuvres, etc., and is usually placed upon a dining table or serving table.

An object of the invention is to provide a server of few parts which are readily separable and permitting at least a pair of trays to be carried by a single standard in separable relation. Yet another object is to provide a server structure in which the center post or standard is equipped with spaced rings for engaging the hubs of the trays to stabilize the trays while reducing the friction thereon, etc. Another object is to provide a server consisting of a base, a center post or standard and trays, all of the parts being readily assembled for supporting the trays in rotatable position on the standard, the structure being collapsible to permit the shipping of the parts in very compact arrangement. A further object is to provide a Lazy Susan server of unique construction and in which the trays are supported for rotation with a minimum of friction and in which the parts are freely separable. Other specific objects and advantages will appear as the specification proceeds.

The invention is illustrated, in a single embodiment, by the accompanying drawing, in which—

Figure 1 is a vertical sectional view of apparatus embodying my invention;

Fig. 2 is a side view in elevation of the server parts in separated condition and in a compact arrangement for shipping;

Fig. 3 a top plan view of the center post or standard; and

Fig. 4 a broken perspective view of a portion of the base.

In the illustration given, 10 designates the base having an annular raised portion 11 and a central recess or socket portion 12. The raised portion or rim 11 may be provided with bosses or rounded ball portions 13, if desired.

The recessed portion or socket 12 of base 10 is adapted to receive the base portion 14 of the standard or center post 15. The post 15 may be of any desired cross sectional shape. In the specific illustration given, the base portion 14 of the standard 15 is generally cylindrical while the upper portion of the standard is somewhat triangular in cross section as indicated by the dotted lines 16 in Fig. 3. The top of the standard 15 is shown provided with a ball 17.

At an intermediate point, the standard 15 is provided with an upwardly extending and pref-

erably circular flange 18, and, if desired, the flange 18 may be provided with anti-friction bosses 19, as illustrated more clearly in Fig. 4; for the base rim 11. Above the flange 18 is a series of three rings 20 which are spaced apart, as shown more clearly in Fig. 1.

Above the base portion 14 of the standard 15 are a second series of rings 20 similar to rings 19, but of greater diameter. A tray 21 is provided with a hub or depending circular flange 22 adapted to frictionally engage the spaced rings 20. The internal diameter of the hub 22 is greater than the diameter of the flange 18, so that the hub 22 can be slipped over the ball 17 at the top of the standard and passed downwardly over the flange 18 and with the base portion of the flange coming to rest over the anti-friction bosses 13 of the base rim 11.

An upper tray 23 is provided with a hub 24 similar to hub 22, but of a lesser diameter, and the lower portion of the hub is supported upon the flange 18, as shown more clearly in Fig. 1.

In the assembly of the server, the standard 15 is placed in position, as shown in Fig. 1, with the base portion 14 received within the socket 12 of base 10. The tray 21 is then passed over the ball 17 and flange 18 to rest upon the rim 11 of base 10. The upper tray 23 is then passed over the ball 17 and its hub is brought to rest upon the flange 18, as illustrated in Fig. 1. The trays may be filled with condiments, relishes, jellies, etc., and they are freely rotatable to bring the desired food item or items in front of the person being served.

When it is desired to ship or store the server, the parts may be disassembled and compactly arranged in various ways. One arrangement is illustrated in Fig. 2. In disassembly, the upper tray 23 is first removed and the lower tray 21 is then raised so that its hub passes over the flange 18 and ball 17. The standard 15 may then be lifted away from the base recess or socket 12.

The assembled server is sturdy even though no device such as screws, etc., are employed. The base recess or socket 12 snugly receives the lower portion 14 of the standard 15. At the same time, the trays 21 and 23 are evenly supported by the wide engagement between their hubs and the spaced rings of the standard. The rings 19 and 20 prevent tilting of the trays under uneven distributions of food loads while at the same time they greatly reduce the friction upon the tray hubs.

While in the foregoing specification I have set forth a specific structure in considerable detail

for the purpose of illustrating one embodiment of the invention, it will be understood that such details of structure may be varied widely by those skilled in the art without departing from the spirit of my invention.

I claim:

1. In a server device of the character described, a base having a central socket recess, a standard having a bottom portion shaped to fit snugly within said recess and having an elongated body tapering upwardly from the base to a top portion of reduced cross section, said standard having on a portion near the bottom a plurality of equi-diameter rings formed coaxially with the standard, and a large tray having a hollow central hub aperture of cylindrical form substantially equal in cross section to the diameter of said rings, said hub portion being provided on the under side with anti-friction bosses adapted to rest on the portion of the base surrounding the socket recess, the base, standard, and tray being freely separable.

2. In a server device of the character described, a base having a central socket recess, a standard having a bottom portion shaped to fit snugly within said recess and having an elongated body tapering upwardly from the base to a top portion of reduced cross section, said standard having on a portion near the bottom a plurality of equi-diameter rings formed coaxially with the standard, said standard being also provided with an annular flange intermediate the said rings and the top and a second set of equi-diameter spaced rings coaxial with the standard and situated immediately above said flange, the diameters of the last-mentioned rings being less than that of the flange and the diameter of the flange being less

than those of the first-mentioned rings, a tray having a hollow central hub aperture of cylindrical cross section and diameter substantially equal to that of the first-mentioned rings, the under side of said hub portion being provided with anti-friction bosses adapted to rest upon the portion of the base surrounding the socket recess, and a second tray similar in structure to the first tray but having the dimensions of its central hub aperture proportioned to fit rotatably over the last-mentioned rings and having anti-friction bosses adapted to rest on the flange, the base, standard, and trays being freely separable one from another.

JAMES F. BARNES.
